JOINTER FOR CIRCULAR SAW BLADES

John B. Engle, Los Angeles, Calif.

Application March 18, 1955, Serial No. 35,105

Term of patent 14 years

(Cl. D37—1)

Figure 1 is a front perspective view of a jointer for circular saw blades, showing my new design; and

Figure 2 is a perspective view from the rear thereof and shown on a smaller scale.

The unshown back of the jointer is plain.

I claim:

The ornamental design for a jointer for circular saw blades, substantially as shown and described.
